C. H. GORE.

SAFETY SIGNAL.

APPLICATION FILED JULY 6, 1920.

1,411,780.

Patented Apr. 4, 1922.

UNITED STATES PATENT OFFICE.

CHARLES H. GORE, OF ST. LOUIS, MISSOURI.

SAFETY SIGNAL.

1,411,780.

Specification of Letters Patent.

Patented Apr. 4, 1922.

Application filed July 6, 1920. Serial No. 394,070.

To all whom it may concern:

Be it known that I, CHARLES H. GORE, a citizen of the United States, residing at the city of St. Louis, in the State of Missouri, have invented certain new and useful Improvements in Safety Signals, of which the following is a specification.

This invention is a safety-first signal to be carried by a trolley car, railroad car, or the like, and adapted to be operated by the rear door or other moving part.

Many accidents occur because persons pass behind a stationary car or the like, forgetting that there may be a moving car approaching on the next track, view of which is obstructed by the stationary car.

Since this carelessness occurs when the stationary car has started into motion, this signal is so arranged as to operate for a short period of time after such car has started into motion.

In the accompanying drawings forming part of this specification, in which like numbers of reference denote like parts wherever they occur,

Figure 1 is a side elevation of the rear part of a trolley car showing the sign constituting part of this invention and two forms of noisemaking danger signals;

Figure 2 shows the device in operation and is a side elevation of the said two danger signals and their connection, respectively, to a battery and to a source of compressed air and the apparatus for operating the said signals;

Figure 3 is a side elevation of part of the said operating apparatus with certain of the parts in positions different from those shown in Figure 2; and

Figure 4 is a view similar to Figures 2 and 3, but showing the device inoperative, i. e., as it is when the car is in motion.

To the rear end of the car 1 is attached a sign 2, bearing a notice of any desirable phraseology adapted to attract attention to the thought that passage behind the rear end of the car without carefulness is dangerous. This sign 2 will be so constructed or painted as to be of striking characteristics by day, so as quickly to attract attention, and it will be illuminated by night for the same purpose. Moreover, an electric bell 3 or the like will be borne thereby or located in juxtaposition thereto. Either said bell 3 or a whistle 4, located on or near the said sign 2, may be used for the purpose of at-

tracting attention thereto and causing people to notice the warning on the sign and to look out for their safety. If desirable, both whistle and bell may be used or either of them.

The bell is operated by the battery 5 in the usual manner. The whistle 4 is operated by compressed air leading through pipe 6 from the reservoir 7, which may or may not be the same tank from which the air brake of the car is operated.

Figure 2 shows the device in operation. In other words, when the car is stopped, the door 8 is opened and the opening of door 8 sets in operation either the bell 3 or the whistle 4 or both. A buzzer or any other noisemaking device may be substituted for the bell 3 or for the bell 3 and whistle 4.

The bracket 9 is fastened to the car wall or roof 10, and carries the cylinder 11. A piston 12 is located in cylinder 11. The spring 13, by pressing on plate 14, forces piston 12 to the position shown in Figure 2. The lever 15 is pivoted at 16. Thus a sliding contact is provided between the lever 15 and segmental plate 17 and in that way a sliding connection exists between lever 15 and plate 17. Thus when lever 15 is moved from the position shown in dotted lines in Figure 3 or from the position shown in Figure 4 to the position shown in full lines in Figure 3, the ringing of the bell 3 occurs. This bell ringing is continuous from the time lever 15 touches segmental plate 17 until moved out of contact therewith. By means of slot 18, lever 15 is slidably and pivotally mounted at 19. When the piston 12 is at the end of its stroke, opposite to the position shown in Figure 2, i. e., as shown in Figure 4, there is no contact with segmental plate 17, and the bell 3 is not ringing. The piston 12 is caused to move toward an inoperative position by means of sliding plate 20, mounted by means of a shaft 21 in a bearing 22. Plate 20 is pushed forward by spring 23. As the door 8 closes, the plate 20 pushes plate 14 carried by piston rod 24 and as a result of the push on piston rod 24, piston 12 causes compression in cylinder 11, while spring 23 is compressed. The door 8 may completely close while spring 23 continues to compress and at the same time the compression in cylinder 11 is relieved by means of the adjustable valve 25, during which time the spring 23 pushes plate 20 and plate 14 together with the piston 12 to the extreme po-

sition shown in Figure 4. The size of the segmental plate 17 and its position are so predetermined with relation to the movement of the plates 20 and 14 and of piston 12, that 5 the bell 3 is allowed to ring for a short period after the door 8 closes with the object of warning people who might rush into danger on the other track immediately after the car bearing the signal has begun to move 10 away.

The same movements of door 8, lever 15, plates 14 and 20, springs 23 and 13, piston rod 24, and piston 12 that ring bell 3 or cause the same to cease ringing or to remain inoperative, likewise produce the same effects with respect to whistle 4, by means of the connection by slot 26 to pin 27, on the revoluble plate 28, which is mounted on arbor 29, containing a two way cock for the control of 15 passage of compressed air from tank 7 through pipe 6 to whistle 4.

Whether, therefore, both bell 3 and whistle 4 are used or only one of them, the operating mechanism is the same with the exception of slot 26, pin 27, plate 28, and the cock within or controlled by arbor 29. Bearing 22 is located in bracket 30, attached to the car door or other moving part in such manner that plate 20 is in alinement with or 20 otherwise adapted to actuate plate 14.

Having thus described this invention, I hereby reserve the benefit of all changes in form, arrangement, order, or use of parts, as it is evident that many minor changes may 35 be made therein without departing from the spirit of this invention or the scope of the following claims.

I claim:

1. In a device of the character described, 40 in combination with a car and car door, a warning signal, means, including means carried by said door and means on a relatively stationary part of said car, for operating said warning signal when the door is opened 45 and for a predetermined length of time after said door is closed.

2. In a device of the character described, 50 in combination with a car and car door, a warning signal, means, including means carried by said door and means on a relatively stationary part of said door, for operating said warning signal while the door is being closed and for a predetermined length of time after said door is closed.

3. In a device of the character described, 55 in combination with a car and car door, a warning signal, means, including means carried by said door and means on a relatively stationary part of said door, for operating 60 said warning signal when the door is opened, during the time said door remains open and for a predetermined length of time after said door is closed.

4. In a device of the character described, 65 in combination with a car and a car door,

a warning signal, means for operating said signal, means for controlling said operating means, for operating the warning signal when the car door is opened and for a predetermined length of time after the door is 70 closed, said control means comprising means upon a relatively stationary part of the car, and means on the car door adapted to engage the last-mentioned means.

5. In a device of the character described, 75 a car, a car door, a warning signal, means, including means carried by said door and means on a relatively stationary part of the car comprising a slidable member and an adjustable retarding device therefor, for 80 operating said warning signal when the car door is opened and for a predetermined length of time after said door is closed.

6. A safety signal of the character described, comprising in combination with a 85 car and car door, a warning signal, a spring-pressed member on the car door, a slidable member on a relatively stationary part of said car in alinement with the first mentioned member, means for actuating the slidable member upon the opening of the car door and for operating the warning signal upon the opening of said door and for a predetermined length of time after the door is closed. 95

7. A safety signal of the character described, comprising in combination with a car and car door, a warning signal, a reciprocable spring-pressed shaft mounted on the car door, a reciprocable spring-pressed 100 shaft mounted on a relatively stationary part of the car in alinement with and adapted to be engaged and reciprocated by the first mentioned shaft, and means connected with the second-mentioned shaft adapted to 105 actuate the warning signal.

8. A safety signal of the character described, comprising a warning signal device, a car door, a spring pressed shaft slidably mounted on the car door, a head on said shaft, a cylinder mounted on a relatively stationary part of the car, a piston in said cylinder, a spring pressed piston rod carried by said piston, a head on the outer end of said piston rod adapted to be engaged by 110 the head on the shaft to actuate said piston, upon the closing of said door, and means carried by said piston rod for actuating the warning signal upon the opening of said door. 115

9. A safety signal of the character described, comprising a warning signal, fluid pressure means for actuating said warning signal, an electrically-operated signal, an electric circuit through said electrically-operated signal, a car door, and means for operating said signal when said door is opened and for a predetermined length of time after said door is closed, said means including a member slidably mounted on 125 130

- the car door, a member slidably mounted on a relatively stationary part of the car and adapted to be engaged and actuated by said first mentioned member and a single means connected to said second mentioned member for controlling said fluid pressure means and said electric circuit, whereby the movement of the car door actuates both the fluid pressure signal and the electric signal.
- 10 10. A safety signal of the character described, comprising in combination with a car and a car door, a warning signal, a shaft slidably mounted on the car door, a cylinder mounted on a relatively stationary part of the car, a piston and a spring pressed rod in said cylinder, the outer end of said piston rod being in proximity to and adapted to be actuated by said shaft, connections between the piston rod and the warning signal whereby the warning signal is actuated by movement of the piston, and an adjustable valve for regulating the compression in the

cylinder to control the period of actuation of said warning signal.

11. The combination of a safety sign, a 25 warning signal in connection therewith, a car door, a bracket mounted on the said car door, a shaft borne by the said bracket, a plate and a spring carried by the said shaft, another bracket supported from the car roof, 30 a cylinder supported by the said bracket, a piston within the said cylinder, a piston rod, a plate borne by the said rod, a spring located between the said plate and the said cylinder, the said cylinder containing an 35 adjustable valve, the said second mentioned plate being adapted to be actuated by the said first mentioned plate and means connected with the said second mentioned plate adapted to actuate the said warning signal. 40

In testimony whereof I hereunto affix my signature.

CHARLES H. GORE.
